[57] CLAIM

The ornamental design for an interchangeable hat, as shown and described.

DESCRIPTION

FIG. 1 is a front elevational view of an interchangeable hat showing our new design;

FIG. 2 is a rear elevational view thereof;

FIG. 3 is a bottom end view thereof;

FIG. 4 is a top end view thereof;

FIG. 5 is a left side view thereof;

FIG. 6 is a right side view thereof;

FIG. 7 is a front view thereof showing one flap folded over; and,

FIG. 8 is a perspective view thereof showing the hat in use. The broken line showing of the human form in FIG. 8 is a for illustrative purposes only and forms no part of the claimed design.
